UNITED STATES PATENT OFFICE.

CHARLES E. H. ARMBRUSTER, OF DENVER, COLORADO.

DYNAMIC OPTOMETER.

1,306,735.

Specification of Letters Patent. Patented June 17, 1919.

Application filed June 21, 1917. Serial No. 176,175.

To all whom it may concern:

Be it known that I, CHARLES E. H. ARMBRUSTER, a citizen of the United States, residing at Denver, in the county of Denver and State of Colorado, have invented certain new and useful Improvements in Dynamic Optometers, of which the following is a specification.

This invention relates to optical instruments 10 of the type known as dynamic optometers, as disclosed in my application for Patent No. 164,497, filed April 25, 1917.

In the instrument shown and described in the above application, a series of charts bearing test-types of graduated sizes, are automatically displayed in successive order and at predetermined distances from the eye of a patient, by movement of the instrument along the visual axis of the eye, and it is the 20 primary object of the present invention to obtain the same result by the intermittent movement of an element upon which a series of test types of graduated sizes are arranged in successive order.

Other objects of my invention reside in providing a mechanism for the automatic operation of the test-type-carrying element which combines simplicity in construction with practicability in use and which may be 30 operated either manually, or automatically by the movement of the instrument relative to a point at which its actuating member is attached.

The above and other objects all of which 35 will fully appear in the course of the following description, I attain by the arrangement of parts and combination of devices which in their preferred form, have been illustrated in the accompanying drawings in the various 40 views of which like parts are similarly designated, and in which—

Figure 1 is a sectional front elevation of my improved instrument,

Fig. 2, a rear elevation of the same,

Fig. 3, a section taken along the line 3—3, Fig. 2,

Fig. 4, a transverse section along the line 4—4, Fig. 3, and

Fig. 5, a section taken along the line 5—5, Fig. 4.

Referring to the drawings by numerical reference characters, 2 designates a handle upon which the operating mechanism of the instrument is supported and which is adapted to be held in the hand of the operator who moves the instrument along the line of vision

of an eye whose dynamic power is being tested.

The handle carries a hollow base 3 having at its upper end a laterally projecting rim 4 surrounded by a circular flange 5 which is broken at a point at the rear of the instrument, as shown at 6 in Fig. 2, to afford access to a milled rim on the rotating element which carries the succession of test-types hereinbefore referred to, for the manual operation thereof, as will hereinafter be more fully described.

The rotary element consists in the preferred construction shown in the drawings, 70 of a wheel which is rotatably supported upon the rim 4 of the base within the flange thereof and which consists of a circular plate 7 surmounted by a cylindrical upstanding rim 8 of slightly reduced diameter.

The edge of the plate is milled to permit of the rotation of the wheel by finger-pressure through the opening provided by the break in the flange of the supporting base, hereinbefore referred to.

The wheel is mounted upon the upper end of a spindle 9 which is rotatably fitted in a tubular sleeve 10 formed integrally below the bottom of the hollow base, and which is secured against longitudinal displacement by 85 a nut 12 screwed upon its threaded extremity projecting beyond the lower end of the sleeve.

The rotary element has beneath its plate and within the hollow base, a gear-wheel 90 13 for its connection with an operating mechanism hereinafter to be described.

The upstanding rim of the wheel has upon its inner surface a series of equidistantly spaced test-types 14 of progressively increasing sizes which preferably are arranged in endless succession.

At the outer surface of the wheel are painted or otherwise affixed, a series of numbers or other identification-marks 15 which 100 correspond in relative position with the test-types on the inside of the rim and which in the operation of the instrument serve to show the operator which one of the series of types is being displayed to the eye of a patient.

The rotary wheel is incased in a hood 16 which is fastened to the flange of the base by means of set-screws 17 and which has a port 18 corresponding with the opening in the flange 5, to afford access to the milled edge of the wheel, and an opening 19 through which the identification numbers 15 on the

outside of the rim 8, may be singly observed from the rear of the instrument.

A vertical sight-tube 20 extending through an opening in the top of the hood has adjacent its ends and at opposite sides, openings 21 and 22 and it has interiorly and opposite said openings, two parallel mirrors 23 and 24 disposed for the reflection of the test-types on the inner surface of the wheel as they are brought in register with the objective opening 22 at the lower end of the sight tube.

The arrangement of the mirrors provides an altiscope by which a person gazing into the sight-opening at the upper end of the tube may see the test-type registering with the opening at the lower end of the same, which faces the interior surface of the rim of the wheel upon which the test-types are affixed.

A housing 25 connected with an opening of the sight-tube intermediate of the points at which the mirrors are disposed, incloses a small incandescent lamp 26 which is connected in a conveniently located electric circuit and serves to illuminate the test-type registering with the objective opening of the tube.

The tube has furthermore an opening 27 above the opening in the hood through which the characters on the outside of the wheel are exposed to sight, for the purpose of illuminating the exposed character and thereby rendering it clearly readable to the operator.

The opening is preferably surmounted by a deflective hood 28 which is closed by a piece of ground glass for the diffusion of the light rays.

In the operation of the instrument, the wheel is intermittently rotated at predetermined intervals during movement of the instrument along the visual axis of the eye of a patient whose dynamic power is being tested, by a mechanism of which a measuring tape 29 is the actuating member.

This tape is wound upon a spring-controlled reel 30 which is mounted for rotation upon a spindle 31 within a casing 32 which is rigidly secured to the base of the instrument by means of a depending bracket 33. A sheave 34 and a pair of rollers 36 at opposite sides of an arm 35, all mounted on the same bracket 33, guide the tape for movement in a substantially horizontal direction, and a pointer 37 fixed adjacent the sheave 34 cooperates with the graduated scale of the tape to designate the distance between the instrument and a point at which the end of the tape is fastened by means of a hook 38.

The tape is provided at predetermined points with tappets 39 to intermittently rotate a transmission member which includes a pinion 40 meshing with the before referred

to gear-wheel 13 of the test-type bearing element.

The transmission member furthermore includes in rigid connection with the pinion, a disk 41 having equidistant peripheral 70 notches 42 adapted to admit the tappets on the longitudinally moving tape, which pass through a groove in the under side of the disk, and thereby impart an intermittent rotary movement to the pinion and the there- 75 with operatively engaging gear-wheel.

A flange 43 on the disk 41 has peripheral indentations arranged in correspondence with the notches 39 to receive a roller at the end of a spring-pressed arm 44 which is 80 pivotally mounted on the base of the instrument.

The arm serves to frictionally hold the transmission member against accidental rotation and to arrest the movement of the 85 rotary body when after each intermittent rotation it is released by a tappet on the longitudinally moving tape.

A spring-pressed friction brake 45 pivoted on a pintle 46 which is mounted on a bracket 90 47 fixed at an end of the spindle 31 around which the tape-reel revolves, normally engages the adjacent side of the reel to retard its rotary movement.

The brake has a thumb-piece 48 readily 95 accessible to the hand in which the instrument is held, for the purpose of releasing the reel from the pressure of the brake whenever this is required in the operation of the instrument.

In testing the dynamic power of the eyes it is often required to ascertain the patient's ability to suppress the accommodating or focusing power of the eye by fixing it at a predetermined distance upon an object of 105 sufficient size to repress any desire to focus.

With this object in view, the series of test-types on the wheel include one which is enlarged out of proportion to the others as shown at 49 in Fig. 1 of the drawings.

The rotary element on which the test-types are arranged has beneath its gear-wheel a cam 50 which is designed to trip a lever 51 when the enlarged suppression type 110 is in register with the opening of the sight-tube, and thereby lift the transmission member to separate its disk from the tape which operates the same.

The member is with this end in view, mounted to move upwardly on the spindle 120 around which it rotates and the lever which is fulcrumed upon the base of the instrument as at 52, has a bifurcated arm extending beneath the member and at the end of its opposite arm a beveled head 53 which is 125 depressed by the cam against the action of a spring 54.

The lever is furthermore provided with a handle 55 extending through an opening in the bottom of the base to provide means for 130

moving it to lift the transmission member at any time it is desired to rotate the wheel without changing the position of the tape.

To measure the lag or over-accommodation of the eye under examination, for the purpose of determining the correct power of accommodation of the patient after the instrument has been moved to a position corresponding with the *punctum proximum*, or 10 nearest point at which the eye can focus, the instrument is provided with a spring-controlled reel 56 upon which is wound a measuring tape 57.

The tape has at its free end a hook 58 for 15 its attachment to a retinoscope or other similar instrument by which the operator may measure the refractive system of the eye, and it is trained around a roller 59 to permit of its end being moved away from 20 the instrument in a direction corresponding with that of the line of vision of the patient.

In testing eyes by the use of my improved instrument, the operator attaches the end of the measuring tape 29 at a point approximately 25 in a vertical plane with the eyes of the patient.

After the patient has been subjected to what is commonly known as the distance test, by focusing the eyes upon a distant 30 test-type to ascertain any errors of refraction in the eyes, the operator places in a trial frame behind which the patient is positioned, lenses which correct the refractive error and thereby establish a substantially 35 normal or emmetropic condition of the eyes.

The operator holding the instrument in the hand with the sight-opening 21 of the tube 20 facing the patient, now moves away from the patient to a point approximately 40 forty inches distant from the trial frame, the measurement being readily ascertained by observing the position of the graduations on the tape relative to the pointer 37.

The operator while holding the instrument 45 in the line of vision of the patient, now moves slightly in the opposite direction and either observes the eye of the patient looking into the sight opening, by means of a retinoscope or other instrument of the same 50 character as is required in the objective test, or ascertains the focusing point of the eye by the subjective test through statements of the patient as to the clearness of the test-types on the wheel which are successively 55 brought in register with the objective opening 22 of the tube 20 and reflected by the mirrors 23 and 24 to be viewed through the sight-opening 21 at the upper end of the tube.

60 When the instrument is brought to a position adjacent the *punctum proximum*, the operator measures the distance between the instrument and the eye of the patient and thereby ascertains the approximate focusing 65 point of the eye, it being observed that the

test-types on the wheel which during movement of the instrument are automatically brought in register with the objective opening of the tube at distances from the point at which the measuring tape is attached, pre-determined by the positions of the tappets on the same, are, as in the instrument described in the application for patent hereinbefore referred to, proportioned in accordance with the lines subtending the normal visual angle of the eyes at corresponding distances from the vertex thereof. 70 75

After the approximate focusing point of the eye or eyes is thus ascertained, the correct power of accommodation is determined 80 by measuring the lag, or, in some cases, the over-accommodation of the eye, by stretching the tape 57 to which the retinoscope is attached, either rearward or forward of the instrument to the point which the operator 85 finds by the use of the retinoscope to be the true focusing point of the patient.

The distance between the retinoscope and the *punctum proximum* previously found, is measured by observing the graduation on 90 the tape 57 which registers with a pointer 60 fixed on a bracket 61 beneath the reel 56.

The operator concludes the test by advancing the instrument toward the patient to the desired reading or working distance, 95 at which point he corrects the vision of the patient by placing lenses in the trial frame which enable him to clearly see the test-type on the chart displayed at that distance and with this knowledge and the knowledge of 100 the accommodating power of the patient, previously obtained, prescribes the required lenses.

During movement of the instrument relative to a point at which the end of the tape 105 is attached, the successive placement of the test-types opposite the objective opening of the sight-tube is produced by the engagement of the tappets on the tape 29 with the notches of the disk 43 which effects an intermittent rotation of the wheel which carries the test-types, at periods corresponding with the predetermined distances from the eye determined by the positions of the tappets on the tape. 110 115

The test-types exposed to view at said distances are as hereinbefore explained proportioned in accordance with the lines subtending the normal visual angle at the same distances from the vertex thereof and it will 120 be understood that these types may consist of letters and words, or, in case the instrument is used to examine the eyes of children of pictorial representations.

When the wheel is turned by hand to a position in which the large or suppression type 49 is exposed to view by registration with the objective opening of the sight-tube, the transmission member is lifted through the instrumentality of the lever 51 and thereby 125 130

placed in an inoperative or idle condition to permit of the instrument being moved back and forth while the patient focuses continuously upon the same chart.

- 5 The operator by observing the numbers exposed through the opening 19 of the hood, knows the particular type which is exposed to view and by pressing the thumb against the milled edge of the wheel he may rotate 10 the same manually to any desired position, independent of the automatic operating mechanism. In fact under certain circumstances, this mechanism may be dispensed with and the types on the wheel exposed only at the 15 will of the operator.

It will be understood that by manual rotation of the wheel the arrangement of the series of test-types relative to the distances at which they are successively exposed, may 20 be varied at will; that if so desired the instrument instead of being held in the hand may be mounted upon an extensible arm which is fastened to a stationary support and that other modifications in the arrangement 25 and construction of the coöperative parts of the instrument may be resorted to within the spirit of the invention as set forth in the following claims.

I claim—

- 30 1. In a dynamic-optometer, a hollow rotary element, having interiorly a series of test types in successive arrangement, a relatively stationary sight-tube having openings within and without said element, reflectors disposed to reflect a type registering with the inner opening, at a point of the tube opposite the other opening, and means for rotating said element to bring said types successively in register with said inner opening.
- 40 2. In a dynamic optometer, a hollow rotary element having interiorly a series of test-types in successive arrangement, a relatively stationary sight-tube having openings within and without said element, reflectors disposed to reflect a type registering with the inner opening, at a point of the tube opposite the other opening, a lamp disposed to illuminate the type reflected by said reflectors, and means for rotating said element to bring said types successively in register with said inner opening.

50 3. In a dynamic optometer, a rotary wheel having an upstanding rim bearing upon its inner surface, a series of successively arranged test-types, a relatively stationary hood incasing said wheel, a sight-tube on said hood having openings within and without the same, reflectors in said tube to reflect a type registering with its inner opening, at a point opposite its other opening, and means for rotating said wheel to bring its types successively in register with said inner opening.

60 4. In a dynamic optometer, a rotary wheel having an upstanding rim bearing upon its

inner surface, a series of successively arranged test-types, a relatively stationary hood incasing said wheel, a sight-tube on said hood having openings within and without the same, reflectors in said tube to reflect a type registering with its inner opening, at a point opposite its other opening, a lamp to illuminate the type reflected by said reflectors, and means for rotating said wheel to bring its types successively in register with said inner opening.

5. In a dynamic optometer, a rotary wheel having an upstanding rim bearing upon its inner surface a series of successively arranged test-types and upon its outer surface a corresponding series of identification marks, a relatively stationary hood incasing said wheel and having an opening to singly expose said marks, a sight tube on said hood having openings within and without the same, reflectors in said tube to reflect a type registering with its inner opening, at a point opposite its other opening, and means for rotating said wheel to bring its types successively in register with said inner opening.

6. In a dynamic optometer, a holder, a movable element thereon bearing in successive order, a series of test types of graduated sizes, a relatively stationary part having a sight-opening through which said test-types may be singly viewed, a reel on the holder, a measuring tape on said reel, having means for the attachment of its end to a stationary support, a second reel on the holder, and a measuring tape on said second reel, having means for its attachment to a retinoscope or the like.

7. In a dynamic optometer, a holder, a movable element thereon, bearing in successive order, a series of test-types of graduated sizes, a relatively stationary part having a sight-opening through which said test-types may be singly viewed, a reel on the holder, a flexible actuating member on said reel, having means for its attachment to a stationary support, and a transmission member coöperative with said actuating member to move said element intermittently at predetermined distances in a movement of the holder relative to a point at which the flexible member is secured.

8. In a dynamic optometer, a holder, a rotary element thereon, bearing in successive order, a series of test-types of graduated sizes, a relatively stationary part having a sight-opening through which said test-types may be singly viewed, a reel on the holder, a flexible actuating member on said reel, having means for its attachment to a stationary support, and a transmission member coöperative with said actuating member to rotate said element intermittently at predetermined distances in a movement of the holder relative to a point at which the flexible member is secured.

9. In a dynamic optometer, a holder, a movable element thereon, bearing in successive order, a series of test-types of graduated sizes, a relatively stationary part having a sight-opening through which said test-types may be singly viewed, a reel on the holder, a flexible actuating member on said reel, having means for its attachment to a stationary support, a transmission member co-operative with said actuating member to move said element intermittently at predetermined distances in a movement of the holder relative to a point at which the flexible member is secured, and means to automatically discontinue the co-operative relation between said members at a determinate distance from said point in the movement of the holder.

10. In a dynamic optometer, a holder, a rotary element thereon bearing in successive order a series of test-types of graduated sizes, a rotary transmission member having a driving connection with said element and including a peripherally notched disk, a reel on the holder, a tape on the reel, having means for its attachment to a stationary support, and tappets on said tape adapted to enter said notches for the intermittent rotation of the transmission-member by a movement of the holder relative to a point at which the tape is attached.

11. In a dynamic optometer, a holder, a rotary element thereon, bearing in successive order a series of test-types of graduated sizes, a rotary transmission-member having a driving connection with said element and including a peripherally notched disk, a reel on the holder, a tape on the reel, having means for its attachment to a stationary support, tappets on said tape adapted to enter said notches for the intermittent rotation of the transmission-member, by a movement of the holder relative to a point at which the tape is attached, and a spring-pressed device to frictionally restrict the movements of the transmission-member.

12. In a dynamic optometer, a holder, a rotary element thereon, bearing in successive order a series of test-types of graduated sizes, a rotary transmission member having a driving connection with said element and including a peripherally notched disk, a reel on the holder, a tape on the reel, having means for its attachment to a stationary support, tappets on said tape adapted to enter said notches for the intermittent rotation of the transmission-member, by a movement of the holder relative to a point at which the tape is attached, said transmission member being adjustable to move its said disk out of the path of said tappets, and means to automatically effect said adjustment at a determinate point in the movement of said element.

13. In a dynamic optometer, a holder, a

rotary element thereon, bearing in successive order a series of test-types of graduated sizes, a rotary transmission member having a driving connection with said element and including a peripherally notched disk, a reel on the holder, a tape on the reel, having means for its attachment to a stationary support, and tappets on said tape adapted to enter said notches for the intermittent rotation of the transmission-member by a movement of the holder relative to a point at which the tape is attached, said transmission member being adjustable to move its said disk out of the path of said tappets, a lever to effect said adjustment, and a cam on the element for the operation of the lever at a determinate point in the rotary movement of the same.

14. In a dynamic optometer, a holder, a movable element thereon, bearing in successive order a series of test-types of graduated sizes, a relatively stationary part having a sight-opening through which said test-types may be singly viewed, a reel on the holder, a measuring tape on said reel, having means for its attachment to a stationary support, a rotary transmission member in driving connection with said element, and co-operative devices on said tape and said member to intermittently rotate the latter at predetermined distances in a movement of the holder relative to a point at which the tape is attached.

15. In a dynamic optometer, a holder, a movable element thereon, bearing in successive order a series of test-types of graduated sizes, a relatively stationary part having a sight-opening through which said test-types may be singly viewed, a reel on the holder, a measuring tape on said reel having means for the attachment of its end to a stationary support, and a manually adjustable brake to frictionally restrict the movement of said reel.

16. In a dynamic optometer, a base, a wheel rotatably mounted thereon and having an upstanding rim bearing a series of successively arranged test-types, a hood secured to said base and incasing said wheel, a sight-tube on the hood having openings within and without the same, reflectors in said tube to reflect a type registering with its inner opening at a point opposite its other opening, a reel on the base, a flexible tape on said reel, having means for its attachment to a stationary support, a rotary transmission member on the base in driving connection with said element, and co-operative devices on said tape and said member to intermittently rotate the member at predetermined distances in a movement of the optometer relative to a point at which the tape is attached.

17. In a dynamic optometer, a base, a wheel rotatably mounted thereon and having an upstanding rim bearing a series of suc-

cessively arranged test-types, a hood secured to said base and incasing said wheel, a sight-tube on the hood having openings within and without the same, reflectors in said tube to reflect a type registering with its inner opening at a point opposite its other opening, a reel on the base, a measuring tape on said reel, having means for its attachment to a

stationary support, and means for rotating the wheel within the hood. 10

In testimony whereof I have affixed my signature in presence of two witnesses.

CHARLES E. H. ARMBRUSTER.
